J. GOICH.
RAILWAY SPIKE.
APPLICATION FILED AUG. 2, 1913.

1,104,884.

Patented July 28, 1914

UNITED STATES PATENT OFFICE.

JOHN GOICH, OF KANSAS CITY, KANSAS.

RAILWAY-SPIKE.

1,104,884.

Specification of Letters Patent. Patented July 28, 1914.

Application filed August 2, 1913. Serial No. 782,589.

To all whom it may concern:

Be it known that I, JOHN GOICH, a citizen of the United States, residing at Kansas City, in the county of Wyandotte and State of Kansas, have invented certain new and useful Improvements in Railway-Spikes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to railway spikes, and has for its principal object to provide a spike which may be driven into an ordinary wood tie for the usual purpose, and automatically clenched in the tie during the 20 driving action. In accomplishing this object I provide the body of the spike with lips and with an auxiliary member which is adapted for engagement by the base of the rail to lift or spread the lips and project 25 same into the tie, so that they may serve as anchors to hold the spike and prevent same from being loosened by the jar incidental to the travel of trains over the track upon which the spike is used.

30 In the accompanying drawings, I have illustrated a preferred form of construction embodying my invention, and will refer to same by reference numerals in the following specification.

35 In the drawings: Figure I is a cross-section of a railway rail, and longitudinal section of a portion of a supporting tie showing a spike constructed according to my invention; the full lines illustrating the spike 40 before it is completely seated and the dotted lines its final position. Fig. II is a section on the line II-II, Fig. I, showing the spike in final position with the anchoring lips spread from the body of the spike. Fig.

45 III is an enlarged perspective view of the spike. Fig. IV is a similar view showing the position of the parts when the spike is in place. Fig. V is a sectional view of the body of the spike, shewing the socket for 50 containing the spreading member. Fig. VI is a detail perspective of the spreading member.

Referreing more in detail to the drawings: 1 designates the body of the spike which is 55 preferably of the ordinary shape, but is provided with a groove 2 in its inner face

which diverges at the upper end into a socket 3 within the head 4 of the body member. At its lower end the groove 2 diverges into a socket 5, which is preferably diamond-shaped, for the purpose presently set forth; the divergence of the groove being such that its sides cut through the sides of the body of the spike and form lips 6 at opposite sides of the groove. The lips 6 are slotted 60 upwardly from the side openings at the lower end of the groove, so that the lips are free from the body and may be spread therefrom, under the conditions presently set forth. The spike also comprises an auxiliary or spreading member 8 having a shank 9 adapted to fit snugly and travel freely 65 within the groove 2, and having a shoe 10 at its lower end fitting within the socket 5 at the base of said groove, the upper and outer faces of said shoe, and the lower and inner faces of the lips 6 being curved, so that when the spreader is drawn upwardly, the travel of the shoe over the lips will tend 70 to move the latter outwardly. The shank 9 has a head 11 located within the lower portion 75 of the socket 3, but spaced downwardly from the lower edge of the main head 4, so that the head of the spreader first contacts the base of a rail when the spike is 80 driven, and retreats upwardly into the socket 3 under the driving action.

In order to insure the engagement of the edge of a rail base with the angle of the spreader head, I construct the shank 9 so 85 that it diverges toward the under face of the head from a point slightly below the said face, and preferably curve the diverging part, so that it will slide freely over the edge of the rail base, thereby insuring contact at the proper point of the head in case 90 the spike should be spaced slightly from the rail.

In using the device, presuming the parts 100 to be constructed as described, when a spike is to be driven, a spreader is placed within the groove 2 with its shoe in the diamond-shaped socket at the bottom of the groove, and with the head located within the socket 3; the length of the shank being such that a 105 space is left above the spreader head, so that such head may be moved upwardly to fit snugly within said socket when the spike is driven fully against the base of the rail. When a spike has been driven into a tie 110 until the head of the spreader is adjacent the base of the rail, the edge of the base

contacts the diverging upper portion of the spreader shank, so that continued driving forces the main spike outwardly into the wood to insure a firm seating thereof, and 5 also insures a firm and close contact of the under face of the spreader head with the base of the rail. Further driving of the spike causes the head of the spreader to contact the rail base and as the spike is 10 forced downwardly the spreader is forced upwardly, lifting the shank 9 and causing the shoe 10 to wedge against the lips 6 and spread same from the sides of the spike body into the tie.

15 It is apparent that the lips when spread as described, and illustrated in the drawings, serve as an anchor to hold the spike against accidental displacement, and that the jarring of the track by passing trains will not 20 tend to loosen the spike, for the reason that any upward movement of the rail base against the head of the spike will tend to pull the spreader upwardly within the spike groove and still further spread the lips 6, 25 or pull the main spike downwardly against the rail base, because of the leverage exerted between the spreader and the lips of the main spike, so that such jarring action instead of serving to loosen the parts tends to 30 still further tighten the same.

While I have described my invention as applied to railway spikes, and have illustrated a specific use, it is apparent that the improvement may be used on docks, bridges, 35 or any place where it is desirable to anchor a spike in place.

If it is necessary to remove the spike, an ordinary crowbar may be pressed under the head of the spike and the latter pried up in 40 the ordinary manner; the upward movement of the spike through the wood causing the lips 6 to be folded back to alignment with the sides of the spike, as the latter is pulled from the wood, the folding back of 45 the lips 6 moving the shoe 10 of the shank 9 downwardly into its socket, so that when the spike is removed the parts are in their original condition. The spike may be used repeatedly as the spreading action on the 50 lips is the same after the lips have been returned to their initial position.

Having thus described my invention, what I claim as new therein, and desire to secure by Letters-Patent, is:—

1. A spike comprising a body member 55 having a groove therein, and having a socket at one end of and communicating with the groove; the sides of the spike being slit above the base of the groove to form lips, and a spreader located in said groove and 60 having a head initially located in said socket, whereby the lips are spread outwardly beyond the side faces of the spike body when the spreader is moved longitudinally in its groove. 65

2. A spike comprising a head and a body member integral with said head, and having a laterally opening groove terminating at its lower end and in an enlarged socket; the sides of the spike being slit longitudinally 70 and transversely adjacent the socket to form loose end lips, a spreader slidably mounted in the groove, and having a head projecting laterally from the upper end of the spike groove and a shoe initially located in the 75 socket and adapted for spreading the loose end lips when the spreader is moved upwardly in its groove, whereby the said lips are spread laterally as the spike is driven.

3. A spike comprising a head and a body 80 member, the former having a downwardly opening socket and the latter having a laterally opening groove communicating with the head socket, and having an enlarged shoe 85 socket at its opposite end; the sides of the spike being slit transversely at the shoe socket and longitudinally thereabove; a spreader slidably mounted in the groove and having a shoe located in the shoe socket, and a head projected transversely from the 90 groove, whereby the spreader head engages a rail prior to the engagement of the rail by the spike head, and whereby the said lips are spread laterally simultaneously with the driving of the spike, substantially as set 95 forth.

In testimony whereof I affix my signature in presence of two witnesses.

JOHN GOICH.
